PIUS BAMMER AND THEODORE GENSMER, OF PORTLAND, OREGON, ASSIGNEES TO N.U. AUTOMATIC BUTTON ATTACHING MACHINE CO., A CORPORATION OF OREGON.

BUTTON-ATTACHING MACHINE.

1,335,315.

Specification of Letters Patent. Patented Mar. 30, 1920.

Application filed March 21, 1913, Serial No. 755,890. Renewed June 17, 1919. Serial No. 304,916.

To all whom it may concern:

Be it known that we, PIUS BAMMER, a citizen of Germany, (who has declared his intention to become a citizen of the United States,) and THEODORE GENSMER, a citizen of the United States, residing at Portland, in the county of Multnomah and State of Oregon, have invented certain new and useful Improvements in Button-Attaching Machines, of which the following is a specification.

Our invention relates to machines for attaching buttons, as to shoes or other objects ready for use, and belongs to that type of machine in which the buttons are successively supplied by the operation of the machine with wire, which, by further operation of the machine being severed into required lengths, one for each button, is formed into staples, which are by the machine driven, one by one, into place and clenched to secure the buttons, respectively, in desired position.

Heretofore, machines of that class have been comparatively complicated, expensive to manufacture, liable to breakage, and to get out of order, and expensive to repair.

From among the objects of our invention the following important ones are selected for enumeration.

30 One object is to reduce the cost of manufacture by reduction of the parts of the machine. Another is, by said reduction, to simplify the operation of the machine. A third is to reduce both liability to breakage and the expense of repairs. A further object is to add to the certainty of the proper operation of the machine, and to practically eliminate any tendency toward deterioration of the operative efficiency of the mechanism in consequence of wear. By our invention also, we provide means for facilitating a supply of buttons of different sizes to the machine.

Other objects will be apparent from the following specification, wherein that which constitutes our invention will be described in detail and succinctly set forth in the appended claims.

In the accompanying drawings,

Figure 1 is a side elevation of one form of embodiment of our invention, showing its parts in normal position at rest, a portion of the standard being broken away.

Fig. 2 is a perspective view, partially broken away, of the staple shaper detached.

Fig. 3 is a front elevation of the upper 55 part of the staple shaping case detached, showing the operative position of the parts at the downward limit of movement of the actuating bar.

Fig. 4 is a section on the line $y-y$ of 60 Fig. 1.

Fig. 5 is a perspective view of the button-holder detached.

Fig. 6 is a side elevation, partially in section, of a portion of the subject matter of 65 Fig. 1 upon an enlarged scale, showing the operative position of parts correspondent to Fig. 3.

Fig. 7 is a perspective view of a part of the actuating member for the staple-shaper 70 and button-holder detached.

Fig. 8 is a front elevation of the subject matter of Fig. 6, with button chute and its sheath removed, but showing the parts in the position which they are shown to occupy in Fig. 1.

Fig. 9 is a similar view, on an enlarged scale, of a portion of the subject matter of Fig. 8, with parts omitted and the face plate of staple shaping case removed to expose the 80 staple-bender and staple-driver in their relations to the staple-shaper.

Fig. 10 is a detail in elevation showing the operation of the staple-driver in its initial movement.

Fig. 11 is a similar view showing the staple-driver in its final clenching operation.

Fig. 12 is a down-looking section on the line $x-x$ of Fig. 9, with addition of the face plate omitted in Fig. 9.

Fig. 13 is a detail elevation of the cut off lower end of the button chute detached, looking toward the side of the chute that is, in use, contiguous to the face plate of the staple shaping case.

Referring to the numerals on the drawings, 1 indicates, by way of illustration of any suitable base, a tripod which carries a standard 2 that may be of any preferred form, for example, the tubular form shown, which at convenient height above the base carries a supporting member 3 for the distinctive mechanism of the machine.

The member 3 is, for convenience only, made to constitute a table, but that feature of it has no functional significance. Its function is that of an assembling member to support the fixed parts in operative rela-

tionship to the movable parts of the machine proper, and to that end it carries a case 13 removed a distance, sufficient for the accommodation of other parts, from an extension 5 tube 4 with which, in connection with the preferred tubular standard 2, the member 3 is, preferably, provided.

The tube 4 serves as a protective covering to the upper end of a reciprocating rod 10, 10 and affords, if so used, a suitable guide support to said rod, which for the purpose may be provided with a head 5 that makes a fit with the bore of the tube and so as to slide snugly within it. The head also affords 15 abutment against the shoulder 6 which it defines about the end of the rod, for a spiral spring 7 that is seated as upon an annular collar 8 to the rod that is secured as by screw threads into the end of the tube 4. The 20 spring 7 exemplifies any suitable means for the yielding uplift of the rod 10, and its particular shape as well as its location within the tube 4 are matters of mere mechanical preference and discretion, to which our invention 25 is intended in no wise to be limited.

The rod 10 may be actuated against the force of the spring 7 by any preferred means, as for example by foot power which a pedal lever 12, pivoted to the tripod and intermediate 30 to the rod as indicated at 11, is adapted to apply.

To the head 5 of the rod is fixed an actuating bar 17, upon whose motion toward and from the member 3, the movements of all the 35 working parts of the machine are, preferably, made to depend.

The primary function of the bar 17 being to operate mechanism to make and then to set a staple, it is next in order to refer 40 to the member 15 which is operatively carried by and preferably within the case 13, and whose chief function is to bend into the form of a staple a section of wire supplied to it. To this end it being essential only 45 that the member 15 and case 13 be made relatively movable, it is preferred that the former be movable and the latter be fixed with respect to the member 3, through which they are assembled.

50 As shown in the drawings, the member 15 is bifurcate and reciprocating within the case 13, but both its bifurcation and its direction of motion are matters of preference only. With this provisory statement of 55 what is essential in the member 15, it will be, for convenience, hereinafter regarded as of the preferred form illustrated unless otherwise indicated and be designated the staple-bender. Proceeding accordingly, the 60 staple-bender is loosely connected to the bar 17 as by a guide rod 16, shown as fixed to the member 15 and working in a bearing provided for it in the bar. From the bar 17 the staple-bender derives motion, during 65 its first stage of movement from a link 49,

that is pivotally secured to and preferably pendent (compare Figs. 3 and 8) from the bar 17, and afterward from a yieldingly interposed expansive spiral spring 18 coiled about the rod 16.

70 Between its legs the staple-bender 15 preferably carries an independently reciprocating staple-driver 19, which is preferably feathered to the member 15. Opposite feathers are preferably provided on the part 19 with correlative grooves 47 in the legs of the part 15 (see Fig. 12) for the reason that in that way the grooves are made to perform the additional function of receiving and guiding the legs of the staple when formed, 80 as hereinafter specified.

The staple-driver 19 derives motion independently of the member 15 from the bar 17, as by impingement of a stud 48 extending from said bar against an arm 20 projecting 85 from the top of the member 19 into a recess 21 provided for it within the case 13, the member 19 being preferably projected toward the stud by an expansive spring 23 interposed between the arm 20 and the end 90 of the recess.

The pendent link 49, above referred to, is of a length to admit of the dropping of its free end 50, under action of its own weight, into position above the staple-bender 15 (see 95 Fig. 8) when the bar 17 reaches its outward limit of motion. When the said bar has made sufficient advance toward the member 3 to effect engagement between the snub-nose 50^a of the link 49 and the rounded 100 shoulder 84 that is disposed on the case 13 in the path of movement of said nose, the link will be, by said shoulder, brushed aside upon its pivot from engagement with the staple-bender 15, and the spring 18 will be 105 substituted, with its yielding resistance to contribute a final presser-foot action, in place of the rigid link. The relative operations of the members 15 and 19 which have been described in the last paragraph result 110 in two distinct movements, to-wit, first that of the members 15 and 19 conjointly, and then that of the latter independently of the former, with the objects in view of severing a section of wire 28 that is, by means hereafter to be specified, kept supplied to the machine, shaping said section of wire into 115 a staple, advancing the staple to a position ready for setting and, by the final action of the driver 19, effecting the setting of the 120 staple.

Preferred means for accomplishing the said results comprehend, in addition to the usual staple forming end upon the driver 125 19, the anvil support 43 and an anvil 44, provided with its cupped face 46, a novel staple-shaper 31 upon the end of bar 25. The shaper 31 has also the usual transverse recess 27, the longitudinal groove 26^a and an overhanging vertically grooved lip, but is 130

distinguished by its adaptation to provision made for its positive and true reciprocatory movement specially timed with respect to those members wherewith it coacts. For 5 that purpose the member 25 is preferably mounted slidingly in a groove 24 through the open end of which projects, upon its limit of outthrust, the shaper 31, to a point at which the end thereof and the front of 10 the staple-bender 15 are substantially flush each with the other. From that point at which it is preferably held normally by a spring 26, the member 25 is designed and adapted to make retreat at the proper time 15 within the groove 24 sufficiently to clear the way to the travel of the driver 19 toward the anvil 44.

As a means for actuating the member 25 against the force of its spring 26, we prefer 20 to employ an arm 25^a which is adapted to accept motion from a stud 40 projecting from the bar 17 and communicate it to the member 25. To that end the arm 25^a may be provided with an oblique face 25^b against 25 which the stud 40 strikes with each movement of the bar 17 toward the supporting member 3, forcing the arm 25^a aside with a wedge action, it being obvious that in this 30 instance the transposition of the inclined plane of the ordinary wedge from one co-operating member to the other in no wise materially alters their combined action. In other words the operation of a true wedge upon the end of the stud 40 against a dis- 35 placeable arm 25^a would be identical in result and principle with the mechanism referred to in the last sentence. To reduce friction, the end of the stud 40 carries, by preference, the roller 41 for engagement 40 with the face 25^b.

In the foregoing specification it was deemed conducive to clearness to omit special reference to the buttons with which the machine, in service, constantly has to do. It 45 is now pointed out that each time the machine makes complete operation it is to accomplish, practically, the setting and securing in place of a button. The means of button supply to the machine and of utilizing 50 the same which our invention affords, are important, both by reason of their structural directness and simplicity, as well as of their certainty and positiveness of operation.

55 The buttons may be fed from a hopper, supported upon the member 3 as by an arm 69, into a chute 79, but our invention, so far as relates to this application, includes, of those elements, only the chute, which be- 60 ing provided with a slit 80, extending from end to end of it, and enlarged as indicated at 87, wherethrough the button shanks of buttons fed and confined within the chute may pass, terminates in spring jaws 88 65 which yieldingly close the lower end of the

chute against discharge of buttons therefrom. Buttons within the chute may descend by gravity alone with entire freedom of movement to the bottom of the chute defined by its jaws 88. Consequently a plu- 70 rality of chutes with accommodation for buttons of different sizes may be used on our machine with complete interchangeability. The chute is secured to the casing by means of the bars 82, fixed in the side 75 plates 83.

By our invention the buttons are supplied without the aid of any intermediate feed mechanism directly to the staple-shaper from the chute, and are thence withdrawn 80 by the first movement of the staple-bender 15 that succeeds the retreat of the staple-shaper 31 before the driver 19. The directness of the operation referred to in the last sentence is accomplished by providing a slit 85 33 in the face plate 32 of the case 13, so that when the chute 79 and the face plate are operatively juxtaposed, as they are when the chute is set into its sheath 81, the slits 33 and 80 are brought together and made to 90 register with each other and with the groove 19^a in the face of the driver 19. Consequently, whenever a button loaded chute is supplied to the machine the shank of the lowermost button, or the one next to the 95 jaws 88, projecting through the slit 80 of the chute, enters, without any opposition, the slit 33 and directly above the groove 26^a on the shaper 31 and there into place to receive a section of staple wire 28, which 100 may be supplied from a reel 30 as through a guide piece 29.

If now, for the moment, it be assumed that with the completion of each outward movement of the bar 17 a feed of the wire 28 is 105 made through the apertured guide piece 29 until the end of the wire abuts against the wall of the case 13 that is opposite the piece 29, it will be readily understood that the successive operations of severing the wire into 110 a staple's length, bending the severed section, and driving and clenching it will follow in regular order upon operation of the mechanism previously specified. It should be observed that the wire is conveniently and 115 therefore preferably cut by the shearwise movement of the bender 15 within and against its case 13.

With each wire feeding operation a section of wire is, in practice, passed through 120 the shank of a button presented to it within the chute 79 itself and above the shaper 31, so that the severed wire section becomes an operative element of the mechanism, and the sole operative means for withdrawing the 125 button from the chute against the yielding resistance of its jaws 88. It becomes therefore of peculiar importance that the wire section should be each time supplied to and fitted within the machine with mechanical 130

accuracy, not only because such accuracy contributes to the proper shaping and disposition of the staple within the grooves 47, but also because upon it depends perfect certainty of operation in the advance of each button from the time of its delivery to the machine to that of its final discharge therefrom.

Therefore, while our machine, to the extent specified hitherto will operate as successfully, perhaps, as machines heretofore known in the art, yet to insure practically perfect certainty of operation and that degree of accuracy required only by the highest standard, we provide in addition to the previously described means of direct delivery of button shanks to the groove 26^a of the shaper 31, a button holder 36 which, carried, as it is preferably upon a sliding bar 35, and working through the enlarged slot 87 in the end of the chute 79, is, by reason of its shape and disposition, adapted to firmly and positively hold each successive button not only firmly against the end of the shaper 31 and the adjacent face of the face plate 32 whose lower end is channeled to a feather edge to meet the shaper, but also with an upward tilting motion whereby the shank of each button as it is presented is positively set into a definite location against the plate 32, its shank confined within the slit 33 and the end of the groove 26^a, whereby possibility of deflection of the wire 28, as through inaccurate presentation of a button shank, which might otherwise occur as through wear in long use, is avoided.

Moreover, by our invention a button once caught between the holder 36 and the shaper 31 is held immovably between them until the staple is fully formed with its legs accurately confined within the grooves 47 ready for the final setting operation of the driver 19. It is then and then only that the simultaneous retreat of the shaper 31 and movement of the holder 36 operate to release the stapled button and permit the staple thereof to descend the grooves 47 under impingement of the driver 19.

The simultaneous operation of the shaper 31 and of the button holder 36 is accomplished by providing upon the sliding bar 35 an arm 37 that is similar to the adjacent arm 25^a, to which it is disposed in operative relationship in respect to its having a beveled face 38 corresponding in function to the face 25^b of the arm 25^a. A spring 39 yieldingly holds the bar 35 in that position in which its button holder 36 tends to engage a button, while actuation of said bar is effected by engagement of a roller 42 on the stud 40 with the face 38 of the arm 37. In the preferred construction of our machine the stud 40, through the simultaneous engagement of its rollers 41 and 42 with the faces 25^b and 38, as above described, becomes

a common actuating member for the two members 25 and 35.

By reason of the relationship of the staple-shaper 31 to the staple-bender, and its disposition upon the end of the bar 25 so as to constitute a part of the longitudinal extent thereof, as well as the open ended disposition of the groove 24 within which, preferably, the bar 25 works with close fitment, we are enabled to provide adequate and convenient means of keeping the working parts clear of obstruction. For example, if by careless operation of the pedal lever 12, or in any wise, two staples or a piece or pieces of wire be caught in or between any of the working parts of the machine proper, the operator may, by the pressure of finger or thumb on the arm 25^a, retract the bar 25 into its groove 24 against the spring 26 until the ends of the groove and of the member 31 are brought flush with each other. The effect will be to strip the member 31, through its sliding action within the groove, of any obstruction that may ride upon it. Quick release of the arm 25^a will effect return of the bar to its normal limit with a snap action which will not only of itself tend to clear the member 31, but will also drive out any obstruction that may offer resistance ahead of its movement.

It was assumed, for convenience, at one place in the foregoing specification that wire 28 is fed from a reel 30 at required intervals to the guide piece 29. Mechanism for the performance of that function is shown in Fig. 8, to which attention is now directed.

At the rear side of case 13 is secured an arm 51, upon the free end of which, upon the pin 53, is mounted a feeder arm 52. To the lower end of the arm 52 is pivoted, at 54, a jaw 55 which is normally held closed, as by a spring 56, against a coacting jaw 57. These jaws preferably have considerable horizontal length and so tend by their bite upon the wire 28 to securely hold the wire, and thereby and by pull upon the wire against its keeper to straighten any kinks that may exist in the wire before it enters the guide piece 29.

On the inner face of arm 52 is carried a bar 59 which has a slot 60 to receive a pin 61, by which the bar 59 is slidably secured to the arm 52. This bar is connected at its lower end with the jaw 55 and extends toward the upper end of arm 52. Upon a pin 62 is pivoted a dog 63 which, engaging the upper end of bar 59, carries at its free end a roller 64.

To the bar 17 is fixed a cam arm 65 disposed in line with roller 64, so that when the bar 17 is driven toward the part 3 the cam arm will, by engagement with the roller 64, actuate the bar 59, through the movement of the dog 63, and open the jaw 55. At this point the cam arm 65 will, in its further movement, engage a roller 66 mounted on a

projection 67 on the adjacent side of the arm 52, and actuate the latter against the tension of a spring 68 which normally attracts it toward the case 13. The return of arm 17 to 5 its normal position, as under expansion of the spring 7, releasing the arm 65 and allowing the jaws 55 and 57 to close upon and grip the wire, permits the tension of the spring 68 to force the wire unwound from the reel 30 10 through the guide piece 29 and the shank of 15 the button on the shaper as and for the purpose already described.

The operation of our machine has been referred to throughout the body of the foregoing specification, but may perhaps to advantage be briefly summarized in the following.

In operation the foot lever 12 will be depressed, thereby operating the rod 10, its 20 head 5, and actuating bar 17 which carries the stud 40 and link 49.

Thereupon, the link 49 engaging the upper end of the member 15, which drives it against the wire 28, after severing it, bends 25 over the staple-shaper 31 the severed wire section into a staple whose legs enter the grooves 47. At this point the snub nose 50^a of the link 49 will engage the rounded shoulder 84 at the upper end of the case 13, there- 30 by disengaging the link and allowing the bar 17 to continue its movement against the yielding resistance of the spring 18. Here the rollers 41 and 42 will simultaneously engage the faces 25^b and 38, respectively, 35 forcing the button holder 36 against the tension of its spring 39, and the staple-shaper 31 against the tension of its spring 26, with the ultimate effect of releasing the button and removing the shaper 31 out of the way of the 40 driver 19. The stud 48 will at the proper point in the movement, by contact with the arm 20 of the driver 19, force it upon the staple held in the grooves 47, with the result of passing the legs of the staple through the 45 object 85, to which the button is designed to be attached, each leg being presented against its respective face 46 of the anvil 44. The final result of the movement of the driver is to clench the staple into place.

50 The same downward stroke of bar 17 will carry the cam arm 65 against the roller 64, depressing the dog 63 against the bar 59 to open the jaw 55, when, upon engagement between the arm 65 and the roller 66, the position 55 of the arm 52, with respect to the wire 28, will be shifted.

Upon releasing the foot lever 12 the bar 17 will be forced to its outer limit by the spring 7, thus allowing the staple-shaper 31 60 to return to position in front of the driver, which, upon release, is restored to its starting position, and the button holder to be drawn rearwardly by the spring 39, which will carry the recurved and forked terminal 65 36 through the slot 87 of the button chute,

where the forked portion will engage and properly situate, to receive its wire, the lowermost button of the chute.

The cam arm 65, being retracted by return movement of the actuating bar 17 and the 70 bar 59 thereby released, permitting the jaw 55 to bite against the jaw 57 upon the wire 28, the tension of spring 68 will actuate the arm 52, which in one movement by aid of its jaws 55 and 57 draws out the wire 28, and 75 thrusts the end thereof through the guide piece 29 and the eye of the button against the opposite side of the case 13, ready for repetition of the operation as above described. Thus it will appear that each forward movement of the actuating bar 17 is calculated to set a button in position, and the return movement thereof to present another button for the machine to set.

What we claim is:

1. In a button attaching machine, the combination with a supporting member, a driving mechanism, staple-forming mechanism and a case, of a movable member working in the supporting member and co-operating with the staple-forming mechanism in the case, and a wedge acting member intermittently engaging and co-operating directly with said movable element to actuate it, said wedge acting member permitting 90 movement of the movable member independently thereof.

2. In a button attaching machine, the combination with a driving mechanism, staple forming mechanism comprising a reciprocal element, and a button holder comprising another and parallelly reciprocal element, of wedge acting mechanism 100 co-operating directly with said reciprocal elements to actuate them.

3. In a button attaching machine, the combination with staple forming mechanism and a button holder co-operating therewith and comprising, respectively, movable elements for performing their respective functions, of wedge acting mechanism common to both movable elements and co-operating directly therewith to actuate them.

4. In a button attaching machine, the combination with staple forming mechanism 115 and a button holder comprising, respectively, movable elements for performing their respective functions, of wedge acting mechanism common to both movable elements and co-operating directly therewith to 120 simultaneously and concomitantly actuate them.

5. In a button attaching machine, the combination with staple forming mechanism comprising a staple-shaper, and a button 125 holder, each provided with an arm, said arms terminating adjacent to each other, of a wedge acting member co-operating with said arms to actuate said shaper and holder.

6. In a button attaching machine, the 130

combination with staple forming mechanism comprising a staple-shaper, and a button-holder normally compelled toward and alining with each other, and each provided with an arm, of a wedge acting member coöperating with said arms to drive them apart.

7. In a button attaching machine, the combination with a supporting member, of a staple-shaper and a button-holder working thereon to and from each other, means for actuating them toward each other, arms upon said shaper and holder, respectively, and wedge acting mechanism coöperating with said arms to separate them and thereby drive the shaper and holder apart.

8. In a button attaching machine, the combination with a supporting member, of a staple-shaper and a button-holder working thereon to and from each other, means for actuating them toward each other, arms upon said shaper and holder, respectively, and a common wedge acting member adapted to separate the arms and thereby drive the shaper and holder apart.

9. In a button attaching machine, the combination with a supporting member of a spring actuated staple-shaper working with close fitment into and out of the supporting member, and provided with a rigidly connected arm adapted to be manipulated to actuate the shaper against the power of a spring for clearing the machine of obstruction.

10. In a button attaching machine, the combination with a supporting member, and a staple-shaper and a button holder, movable in opposite directions only and adapted to confine between them a button, of a staple-bender coöperative with the shaper to form a staple, and driving mechanism adapted to operate the shaper and holder only after the staple is completely formed.

11. In a button attaching machine, the combination with a supporting member, and a staple-shaper and a button-holder, movable in opposite directions only and adapted to confine between them a button, of means for feeding staple wire through the shank of the button while so held, and a common driving mechanism adapted to operate the shaper and holder to release the button only after the wire feeding operation.

12. In a button attaching machine, the combination with a supporting member, a staple-bender, and a staple-shaper and a button-holder, movable in opposite directions only and adapted to confine between them a button, of means for feeding staple wire through the shank of the button while so held, and driving mechanism adapted to operate the shaper and holder to release the button only after the wire feeding and staple bending operation.

13. In a button attaching machine, the

combination with a driving mechanism, and a case containing a staple-bender and a staple-driver and provided with a slit to admit a button shank into operative proximity to the bender and driver, of a movable staple-shaper working to and from said slit, a button-holder adapted to present a button shank within said slit and to hold it there during the operation of mechanism provided for supply of staple wire through said shank, and a single means for simultaneously engaging and actuating the shaper and holder.

14. In a button attaching machine, the combination with a driving mechanism and a case containing a staple-bender and a staple-driver and provided with a slit to admit a button shank into operative proximity to the bender and driver, of a movable staple-shaper working to and from said slit, a button-holder adapted to present a button shank within said slit and to hold it there during the operation of mechanism provided for supply of staple wire through said shank, and until, by coöperation of the bender and shaper, a staple has been completely formed, a single means for simultaneously engaging and actuating the shaper and holder.

15. In a button attaching machine, the combination with its supporting member, case, and staple-bender within the case, of a slotted face-plate for the case, and a staple-shaper and a button-holder working against opposite sides of the face-plate and adapted to confine a button between them against the face-plate with the button shank in the slit thereof, and a single means for simultaneously engaging and actuating the shaper and holder.

16. A button attaching machine comprising a supporting member, an anvil, an actuating bar and a case between said bar and anvil, a staple-shaper working on said supporting member in operative relationship to said anvil, and standing normally in operative proximity thereto, a staple-bender operatively communicating with said actuating bar and mounted on the case to coöperate with the staple-shaper and bend a staple, an arm extending substantially parallel to the staple bender from the staple-shaper, a depending stud on the actuating bar adapted to engage said arm to actuate the staple-shaper, and means for operating the actuating bar to operate the staple-shaper and staple-bender.

17. A button attaching machine comprising a supporting member, an anvil, an actuating bar and a case between said bar and anvil, a staple-shaper working on the supporting member in operative relationship to said anvil, and standing normally in proximity thereto, a staple-bender operatively communicating with said actuating bar and

- mounted on the case to coöperate with the staple-shaper to bend a staple, an arm extending from the staple-shaper, a button chute having an opening in its end terminating opposite the staple-shaper, a button-holder slidably mounted on the supporting member to work in said chute opening, an arm projecting from the button-holder adjacent to that of the staple-shaper, a stud 5 on the actuating bar adapted to separate said arms and means for imparting motion to the actuating bar simultaneously to operate the staple-shaper and the button-holder and independently the bender.
18. A button attaching machine comprising a supporting member, an anvil, an actuating bar, and a case between said bar and anvil, a staple-shaper working in said supporting member in operative relationship 10 to said anvil, and standing normally in operative proximity thereto, a staple-bender connected to said actuating bar and mounted on the case to coöperate with the staple-shaper to bend a staple, an arm extending from the staple-shaper, a stud on the actuating bar adapted to engage said arm to actuate the staple-shaper, a button holder slidably mounted in the supporting member, a staple-driver having a projection, a stud on the actuating bar adapted to engage said projection, and means for operating the actuating bar to actuate the staple-bender, simultaneously to separate the staple-shaper and the button-holder, and then to actuate 15 the staple-driver.
19. A button attaching machine comprising a supporting member, an anvil, an actuating bar and a case between said bar and anvil, a staple-shaper working in said supporting member in operative relationship 20 to said anvil, and standing normally in operative proximity thereto, a staple-bender connected to said actuating bar and mounted on the case to coöperate with the staple-shaper to bend a staple, an arm extending from the staple-shaper, a button-holder slidably mounted in the supporting member, a staple-driver having a projection, a stud on the actuating bar adapted to engage said projection, and means for operating the actuating bar to actuate the staple-bender, simultaneously to separate the staple-shaper and the button-holder, and then to actuate 25 the staple-driver.
20. A button attaching machine comprising a supporting member, an anvil, an actuating bar and a case between said bar and anvil, a staple-shaper working in said supporting member in operative relationship 30 to said anvil, and standing normally in operative proximity thereto, a staple-bender connected to said actuating bar and mounted on the case to coöperate with the staple-shaper to bend a staple, an arm extending from the staple-shaper, a button-holder slidably mounted in the supporting member, a staple-driver having a projection, a stud on the actuating bar adapted to engage said projection, and means for operating the actuating bar to actuate the staple-bender, simultaneously to separate the staple-shaper and the button-holder, and then to actuate 35 the staple-driver.
21. In a button attaching machine, a supporting member, a staple-shaper mounted slidably thereon, a button hopper mounted on the supporting member, a raceway leading 40 from the hopper to the staple-shaper, a button-holder slidably mounted on the supporting member, having a terminal adapted to oppose that of the staple-shaper, and movable only in opposite direction thereto, 45 and means operable by the machine for automatically delivering buttons from the hopper to the raceway and for positively engaging and separating the staple-shaper and button-holder.
22. In a button attaching machine, the combination with a staple-shaper and a button-holder comprising coöperating movable elements for holding a button therebetween, of means carrying staple severing 50 and setting elements provided with a common wedge acting member coöperating directly with said movable elements to actuate them.
23. In a button attaching machine, a supporting member, an actuating bar mounted to move reciprocally thereon, a staple-shaper, mounted to move transversely in the same member, yieldingly held in normal position, and having a rigid upstanding arm, 55 and a stud extending from the actuating bar parallel to said arm and adapted to engage said arm for operating the staple-shaper.
24. In a button attaching machine, a supporting member, an actuating bar mounted to move thereon, a staple-shaper mounted to move transversely in the said member and having an upstanding arm provided with a beveled terminal and yieldingly held in 60 normal position, a button-holder slidably mounted adjacent the staple-shaper, having an upstanding arm having a beveled terminal oppositely disposed to that of the staple-former, and a recurved portion to oppose the projecting end of the staple-shaper, 65 means for yieldingly holding the button-holder in position proximate to the shaper and a stud extending from said actuating 70

bar adapted to engage said beveled terminals for actuating the staple-shaper and the button holder, in opposite directions.

25. In a button attaching machine, a supporting member, an actuating bar mounted to move thereon, a staple-shaper mounted to move transversely in the said member and having an upstanding arm provided with a beveled terminal and yieldingly held in normal position, a button-holder slidably mounted adjacent the staple-shaper, having an upstanding arm having a beveled terminal oppositely disposed to that of the staple-former, and a recurved portion to oppose the projecting end of the staple-shaper, means for yieldingly holding the button-holder in position proximate to the shaper, a stud extending from said actuating bar adapted to engage said beveled terminals for actuating the staple-shaper and the button holder, in opposite directions, and a button chute having in its inner face a slot adapted to receive the shank of a button and terminally disposed between the end of the

25 staple-shaper and the button-holder, said chute being further provided with an opening to receive the recurved portion of the button-holder.

26. In a button attaching machine, a supporting member having grooves formed in the upper surface thereof, a button-holder

adapted to slide in one of said grooves, and a staple-shaper adapted to slide in the other of said grooves.

27. In a button attaching machine, a supporting member having adjacent parallelly disposed grooves in the upper surface thereof, a button-holder mounted in one of said grooves, and a staple-shaper mounted in the other of said grooves. 35

28. In a button attaching machine, a supporting member having grooves formed in the upper surface thereof, a button-holder slidably mounted in one of said grooves, a staple-shaper slidably mounted in the other 45 of said grooves, upstanding arms formed on each of said slideable members, and means for engaging said arms to operate the members.

29. In a button attaching machine, a supporting member having a button-holder and a staple-shaper slidably mounted therein, said button-holder having a recurved portion adapted to aline and coöperate with said staple-shaper. 50

In testimony whereof we affix our signatures in presence of two witnesses.

PIUS BAMMER.
THEODORE GENSMER.
